C. P. Goepel.

UNITED STATES PATENT OFFICE.

RICHARD BAER, OF NEW YORK, N. Y.

COLLAR.

1,427,752.

Specification of Letters Patent. Patented Aug. 29, 1922.

Application filed September 24, 1919. Serial No. 326,037.

To all whom it may concern:

Be it known that I, RICHARD BAER, a citizen of the Republic of Czecho-Slovakia, and resident of the borough of Manhattan, in the city, county, and State of New York, have invented certain new and useful Improvements in Collars, of which the following is a specification.

This invention relates to collars, and more particularly to soft or unstarched collars of the turnover type.

Broadly considered, the invention has for its primary purpose and object to provide simple and effective means on the front part of the collar at its free ends, which will support the connected ends of the collar and hold the same straight and smooth and prevent the wrinkling or crushing of the collar ends.

It is another and more particular object of my invention to provide a device for the above purpose, embodying relatively rigid stays or supports, and means on the front portion of the collar at its free ends to removably receive said stays together with a detachable connecting means between the stays whereby the opposed ends of the collar are effectively held against a relative lateral movement.

The invention further contemplates the provision of a device for the above purpose which may be easily and quickly applied to or removed from the collar and will support the parts of the collar even though they may become wet and limp, so that even in such an extreme case, a proper fitting and neat appearance of the collar will be maintained.

It is a further general object of my invention to provide a collar support, the several parts of which are simple and durable in construction and capable of manufacture at comparatively small cost.

With the above and other objects in view, the invention consists in the provision of a collar support as above characterized, and in the form, construction and relative arrangement of the several parts thereof, as will be hereinafter more fully explained, illustrated in the accompanying drawing and subsequently incorporated in the subjoined claims.

In the drawing wherein I have illustrated one practical embodiment of the invention, Fig. 1 is a perspective view of a soft turn-down collar having its ends connected and

provided with my improved supporting means;

Fig. 2 is a fragmentary perspective view, the ends of the collar disconnected and separated, and the front portions turned up to more clearly disclose the arrangement of the supporting stays;

Fig. 3 is a detail horizontal section through the connected collar ends;

Fig. 4 is a vertical sectional view; and

Fig. 5 is a detail perspective view of one of the stay members.

Referring in detail to the drawing, 5 and 6 respectively designate the outer and inner folds of a turndown collar. In the class of collars to which this invention relates, the two folds of the collar are each constructed of two thicknesses of linen or other suitable material, stitched together. The collar as it is placed upon the market in condition to be worn, is unstarched so that all parts thereof are soft and flexible. The inner fold of the collar terminates in the tabs or extensions 7, adapted for lapping engagement upon each other, and is provided with the usual registering buttonholes 8 to receive the button which is arranged in the neck band of the shirt. A third buttonhole 9 is likewise provided in the collar fold 6, adjacent its lower edge and at the center thereof to receive the rear collar button.

A very common objection to such collars is that they will not retain a neat and proper fitting appearance at their connected front ends for any considerable length of time. This is especially true in hot weather, as the collar will then become wet with perspiration and the conspicuously exposed front portion thereof will not stand up but will sag and wrinkle. For the purpose of obviating this objection, I have provided the relatively rigid stays or supports 10 which may be formed of thin nickelized steel, or as an equivalent thereof, pyralin, celluloid or other material which will not rust or corrode. While these stays have sufficient inherent flexibility to permit the collar ends to conform to the contour of the wearer's neck, they will not bend or buckle to such an extent that the collar will get out of shape. These stays 10 are arranged upon the inner side of each front end of the outer collar fold 5, and they are preferably slightly curved longitudinally as seen in Fig. 5 of the drawings. The inner thickness of the material from which the collar

fold is formed is slit or cut as at 11 to receive one end portion of the stay, the edge of said slit being stitched or otherwise reinforced. The end of the collar fold is cut to provide a downwardly extending point indicated at 12, and the slit 10 is located at a point substantially midway between the extremity of this point and the upper edge of the collar. A loop 13 of linen is secured to the inner face of the fold 5 adjacent to its connection with the collar fold 6 and in spaced relation to the slit 11. In applying the stay, the point 12 of the fold 5 is lifted and the tapering end 14 of the stay inserted through the loop 13 and then through the slit 11. At its other end, the stay is turned or bent upon itself as at 15 to provide a stop engaging the end of the loop 13 and also serves as a convenient finger piece whereby the stay may be withdrawn. It is further to be observed that this end 15 of the stay engages with the under side of the collar at its upper edge at the point of connection of the two folds 5 and 6, and thus serves to prevent the collapse of the collar folds at the seam line.

In applying the stays, the concave sides are outwardly disposed, or next adjacent to the material of the collar fold so that they will direct the pointed front ends 12 of the fold 5 outwardly. The portion of each stay between the slit 11 and the loop 13 remains exposed or uncovered and before inserting the stay, a loop of linen or other non-elastic or elastic material 16 is slipped upon one of the stays and is free to shift upon the intermediate portion thereof. To the connected ends of this linen loop a hook 17 is attached. This hook is adapted to be engaged over the inner edge of the other stay on the opposed end of the collar as seen in Figs. 1 and 3 of the drawing. Thus the collar ends are effectively held against a lateral movement away from each other. The stays 10 are arranged as near as possible to the front diverging edges of the collar ends, and when the stays are connected, the linen loop 16 extends horizontally over the connected extension 7 of the inner collar fold 6 and above the button engaged through the button-holes 8.

In order to more securely hold the ends of the inner fold 6 of the collar in connected relation and to prevent relative movement of the extensions 7 at their upper edges, I provide upon the outer face of one of these extensions which is disposed next adjacent to the neck of the wearer, an eye 18 which is located at a point slightly within the line of the front edge of the outer collar fold 5. A complementary hook 19 is secured to the inner-side of the other end flap or extension 7 on the fold 6. After the extensions 7 have been buttoned together at their lower edges, the hook 19 is engaged in the eye 18 so as

to securely hold the extensions in connected relation adjacent to their upper edges.

From the above description, it will be apparent that when the collar is applied to the neck band of the shirt, and the vertically disposed stays 10 on the inner sides of the opposed ends 12 of the outer collar fold connected to each other by the loop 16, these collar ends will be held in their erect positions. The wearer may move his head freely without danger of relative displacement of the collar ends, or destroying the neat appearance of the collar. If the collar should become wet through perspiration or other cause, the connected stays 10 will nevertheless hold the ends of the collar against collapse so that they will not become wrinkled or crushed. When the collar is to be laundered, the stays 10 can be readily removed from the collar ends together with the connecting loop 16. It will be observed from reference to Fig. 3 that the loop 18 is bent outwardly slightly so that the hook 19 when engaged therein, will not cause discomfort to the wearer. The loop or connecting strip 16 may be secured across the space between the ends of the outer fold 5 of the collar beneath the knot of a tie for supporting the tie knot.

In the accompanying drawing, I have illustrated one construction and application of the improved collar stays or supports which I have found to be very effective in practical use. It will be understood, however, that the several parts of the device may be constructed in other forms than herein disclosed and slight modifications may also be resorted to in the association and arrangement of the several parts upon the collar. Accordingly I reserve the privilege of adopting all such legitimate changes as may be fairly embodied within the spirit and scope of the invention as claimed.

I claim:

1. In combination with a collar of the kind described relatively rigid stays on the front portion of the collar adjacent to its free ends, and means directly engageable with said stays and independent of said front portion of the collar for connecting said stays to each other across the ends of the collar when in normal wearing position.

2. In combination with a collar of the kind described, relatively rigid stays on the front portion of the collar adjacent to its free ends, and detachable means directly engageable with said stays and independent of said front portion of the collar for connecting said stays to each other across the ends of the collar when in normal wearing position.

3. In combination with a collar of the kind described, relatively rigid stays on the front portion of the collar adjacent to its free ends, and means removably interlocked

upon one of the stays independently of the front portion of the collar for detachably connecting said stays to each other across the ends of the collar.

5. 4. In combination with a collar of the kind described, relatively rigid stays on the front portion of the collar adjacent to its free ends, each free end of the collar having at its inner side an interrupted pock-
10 et adapted to removably receive a stay and with an intermediate part of the stay ex- posed, and a loop adapted to be secured about the said exposed intermediate portion of one stay and having a hook adapted
5 to detachably engage the exposed portion of the other stay for detachably connecting the stays.
5. In combination with a collar of the kind described, relatively rigid stays on the front portion of the collar adjacent to its free ends, a loop slidably engaged upon the intermediate portion of one of the stays and removable therefrom, and a hook carried by said loop adapted to be detachably en-
25 gaged with the other stay across the ends of the collar.
6. In combination with a collar of the kind described, relatively rigid stays, and means on the inner side of each outer fold
30 of the collar adjacent to its front end to re- movably receive one of the stays, each stay at its upper end being turned upon itself to provide a roll adapted to engage and sup- port the collar folds at the seam line con-
35 stituting the upper edge of the collar.
7. In combination with a collar of the kind described, relatively rigid stays, said

collar having means at its ends to removably receive said stays, and means independently of the front portion of the collar for con- 40 necting the stays to each other and sepa- rable therefrom, said means extending across the connected collar ends and having limited shifting movement longitudinally of the stays.
45

8. In a soft collar having a band and fold- over top, stiffeners located on said top ad- jacent the vertical edges of the ends of the top and detachable means connecting the ends of the top, said means being secured to 50 the stiffeners.

9. In a soft collar having a band and fold- over top, stiffeners located on said top ad- jacent the vertical edges of the ends of the top, said stiffeners extending substantially 55 the full width of the top, means for detach- ably connecting said stiffeners to the top in fixed position and a detachable strip pro- vided at each end with means for engaging said stiffeners and adapted to hold in posi- 60 tion the ends of the top.

10. In a soft collar having a band and fold-over top, stiffeners located on said top ad- jacent the vertical edges of the ends of the top, said stiffeners extending substan- 65 tially the full width of the top, means for detachably connecting said stiffeners to the top in fixed position and a detachable elastic strip provided at each end with means for engaging said stiffeners and adapted to hold 70 in position the ends of the top.

In testimony that I claim the foregoing as my invention, I have signed my name.

RICHARD BAER.
